COMBINED METER CASE AND COVER

Roscoe A. Ammon, Manchester, N. H.

Application May 2, 1955, Serial No. 35,766

Term of patent 14 years

(Cl. D52—1)

Fig. 1

Fig. 3

Fig. 1 is a front view of a combined meter case and cover showing my new design;

Fig. 2 is a side view; and

Fig. 3 is a section view of the meter case cover.

I claim:

The ornamental design for a combined meter case and cover, substantially as shown.
